UNITED STATES PATENT OFFICE.

HARRY S. VROOMAN, OF CHICAGO, ILLINOIS.

DESIGN FOR FIRE-BRICK.

SPECIFICATION forming part of Design No. 30,289, dated February 28, 1899.

Application filed February 3, 1899. Serial No. 704,429. Term of patent 14 years.

To all whom it may concern:

Be it known that I, HARRY S. VROOMAN, a citizen of the United States, residing at Chicago, Cook county, Illinois, have invented and produced a new and original Design for Fire-Brick, of which the following is a specification, reference being had to the accompanying drawings, forming a part thereof.

Figure 1 is a perspective view of a fire-brick, showing my new design. Fig. 2 is an end view of the same.

As shown in the drawings, my design for fire-brick is rhomboidal in general outline. It is formed with the upper and lower edges a a' parallel, but with the cross-diameter of the edge a slightly greater than the corresponding diameter of the edge a' . The side faces b b' of the brick taper throughout their vertical diameters from the upper edge a inwardly to the lower edge a' . The side face b is broken at a point beginning at about the center of its vertical diameter with an angular depression c , which extends throughout the length of the brick. This depression is

formed by inwardly-inclined faces c^2 c^3 of 25 equal width, which meet at a slightly obtuse angle. The depth of the depression at its widest point is substantially one-fourth of the cross-diameter of the brick. The side face b' is broken by an angular elevation c' , which 30 extends throughout the length of the brick and corresponds in its dimensions exactly with the depression c on the opposite face. The ends d of the brick, only one of which is shown, are plane and parallel and exact counterparts of each other. 35

Having thus described my invention, what I claim as new, and desire to secure by Letters Patent, is—

The design for fire-brick, substantially as 40 herein shown and described.

In testimony whereof I affix my signature in presence of two witnesses.

HARRY S. VROOMAN.
